W. A. DANIELS.
WHIFFLETREE COUPLING MEANS.
FILED JULY 2, 1921.

Inventor
W.A. Daniels.

By Watson E. Coleman

Attorney

UNITED STATES PATENT OFFICE.

WILLIAM A. DANIELS, OF DERMOTT, ARKANSAS.

WHIFFLETREE-COUPING MEANS.

Application filed July 2, 1921. Serial No. 482,246.

To all whom it may concern:

Be it known that I, WILLIAM A. DANIELS, a citizen of the United States, residing at Dermott, in the county of Chicot and State 5 of Arkansas, have invented certain new and useful Improvements in Whiffletree-Coupling Means, of which the following is a specification, reference being had to the accompanying drawings.

10 This invention relates to whiffle-trees, and more particularly to a double-tree.

It is an object of the invention to provide a device of this character having novel means whereby single-trees may be 15 connected to the double-tree and prevented from disengagement regardless of the direction of movement of the single-tree, or the amount of strain applied to the single-trees. It is also an object of the invention to provide 20 novel means for connecting single-trees to a double-tree, said means being so arranged that accidental unfastening or release of the single-trees is impossible.

It is a further object of the invention to 25 provide novel coupling means for whiffle-trees including a keeper and a latch member, said latch member being detachably connected to the whiffle-tree, one portion of said latch member being arranged to extend 30 through the keeper, while the extremity of said latch member is adapted to engage the keeper.

With these and other objects in view the invention consists in the improved construction and arrangement of parts to be hereinafter more particularly described, fully claimed and illustrated in the accompanying drawings, in which:—

Figure 1 is a plan view of a double-tree, 40 showing the coupling means applied.

Figure 2 is an end elevation of the structure shown in Figure 1.

Figure 3 is a perspective view of one of the latch members, and

45 Figure 4 is a perspective view of one of the keeper members.

Referring to the drawings, 5 designates a whiffle-tree of conventional form preferably of the double-tree type, but it is of course obvious that the invention may also 50 be used in connection with single-trees.

It has been found that with the coupling means previously used for connecting single-trees to double-trees, that considerable difficulty is experienced in preventing the single-tree from becoming disengaged from the

double-tree upon movement of the single-tree in certain directions. To overcome this disadvantage, the invention provides novel coupling means embodying a keeper member 7 which consists of a substantially L-shaped member, the portion 8 of said member being secured to the rear face of the whiffle-tree 5, while the portion 9 of said member extends over the end face of the 65 whiffle-tree and beyond the front face thereof, the outer end of the portion 9 having a relatively large opening 10, the portion of the keeper member adjacent the opening being enlarged to reinforce the opening. The 70 keeper member is secured to the whiffle-tree by means of bolts 10^a, said bolts extending through the whiffle-tree and having their threaded ends 11 projecting beyond the front face of the whiffle-tree. By the novel construction of the keeper member 7, danger of breakage or accidental disconnection is 75 eliminated, as the portion 9 is not connected to the end face of the whiffle-tree, the connection being through the portion 8, so that 80 any amount of strain may be applied to the keeper member by the draft means.

In connection with the keeper member 7, a latch member 12 is provided, said latch member consisting of a strip of material 85 having openings 13 in its end portion 14 for the reception of the ends 11 of the bolts 10^a, said end portion of the latch member being adapted to engage the front face of the whiffle-tree. The opposite end portion 90 15 of the latch member is substantially round in cross section, and is extended from a point adjacent the outermost bolt 10^a, in angular relation to the end portion 14 of the strip, and outwardly toward the end of the 95 whiffle-tree. The extremity of said end portion 15 is extended back upon said end portion to substantially form a loop 16, the end portion of the loop being formed into a hook 17 so that the extremity of the portion 15 100 is substantially S-shaped. The purpose of extending the end portion 15 outwardly toward the end of the whiffle-tree is to permit a portion of the latch member to extend through the opening 10 of the keeper and 105 permit the loop 16 to extend beyond the outer side face of the keeper member 7.

In the use of the device, the end portion 14 of the latch member 12 is passed through the opening 10, and the single-tree A engaged with the loop member 16. The hook 17 of the latch member is then engaged

with the intermediate portion of the portion 9 of the keeper so as to lock the single-tree within the loop member 16. The end portion 14 is then moved into engagement with 5 the front face of the whiffle tree and positioned by means of the threaded ends of the bolts 10. Thumb nuts 18 are then engaged with the ends 11 of the bolts to firmly 10 secure the end portion 14 of the latch member to the whiffle-tree. One of the coupling means is provided for each end of the double-tree, and if desired, may be constructed for attachment to the ends of single-trees.

To properly connect the double-tree, to 15 the vehicle, there is provided a novel form of clip comprising a U-shaped body member 19, adapted to engage the intermediate portion of the double-tree, the ends of said body member having registering openings 20, said 20 ends extending beyond the rear face of the whiffle-tree. A novel connecting and hitching member 21 is provided, said member consisting of a length of material having its end portions threaded as at 22, while its intermediate portion is bent substantially U-shaped. The end portions 22 are adapted to extend through openings 20, while nuts 23 are threaded on said end portions so as to 25 draw the body member or clip into binding engagement with the double-tree, the portion 30 of the member 21 between the inner faces of the ends of the clip and the junction of the U-shaped intermediate portion of the member 21 being arranged to engage the rear face 35 of the double-tree so as to prevent lateral movement of the clip. At the same time, the U-shaped intermediate portion of the member 21 extends rearwardly to substantially provide an eye whereby the double-tree may 40 be hitched to the vehicle. If desired, the same connection may be used in connection with the single trees.

From the foregoing it will be readily seen that this invention provides novel coupling 45 means for connecting single-trees to double-trees, wherein the single-tree is unlimited in its movement and yet is positively locked

against accidental disengagement. In addition to this, the loop portion 16 is relieved of part of the strain of draft by means of the 50 end of the opening 10 serving as a brace for the portion of the loop or latch that extends through the opening, so that the point of greatest strain is reinforced. Furthermore, the hook 17 is urged into engagement with 55 the keeper when the end portion 14 of the loop member is applied to the whiffle-tree and any strain on the loop member 16 will only tend to more firmly bind the hook member 17 on the keeper member 7. The 60 single-tree may be quickly and easily detached when desired, by loosening the nuts 11 so as to disengage the hook 17 from the keeper and permit the latch member to be disengaged from the double-tree. This feature eliminates the use of a ring for connecting the single-tree to the double-tree. In addition to this, it permits the single-tree to be disposed in spaced relation to the double-tree so that danger of contact of the 65 coupling member or the single and double-trees with each other is prevented, and all of these features are possessed by a device that is simple in construction, as it is composed of only two parts which will last indefinitely. 75

What is claimed is:-

Whiffle tree coupling means comprising an L-shaped keeper member adapted to engage the rear and end faces of the whiffle-tree, a portion of said keeper member projecting 80 beyond the whiffle-tree and having an opening in its end, and a latch member adapted to engage the front face of the whiffle-tree, one end of said latch member extending outwardly toward the end of the whiffle-tree, 85 said end portion of the latch member extending through the opening and back toward the keeper, into engagement with the keeper and rearwardly of the opening to provide a loop member, said loop member extending to one side of the keeper.

In testimony whereof I hereunto affix my signature.

WILLIAM A. DANIELS.
